UNITED STATES PATENT OFFICE.

JOHN LAVIGNA, OF CHICAGO, ILLINOIS, ASSIGNOR TO MARTIN LANGNER, OF CHICAGO, ILLINOIS.

RAILROAD CLAMP.

Application filed February 23, 1924. Serial No. 694,697.

To all whom it may concern:

Be it known that I, JOHN LAVIGNA, a citizen of the United States, residing at Chicago, in the county of Cook and State 5 of Illinois, have invented new and useful Improvements in Railroad Clamps, of which the following is a specification.

This invention relates to temporary supports especially adapted for use in railway 10 operations and particularly on repair jobs.

Briefly stated, an important object of this invention is to provide a support which may be quickly brought into use to take the place of a tie during the removal of 15 a tie whereby the rail is firmly supported.

A further and equally important object 20 of the invention is to provide a temporary support for rails which may be quickly placed in position without removing the rail and without inconvenience.

A further object of the invention is to provide a temporary support of the character specified which is of highly simplified construction, durable in use, and cheap to 25 manufacture.

Other objects and advantages will be apparent during the course of the following description.

In the accompanying drawing forming 30 a part of this application and in which like numerals are employed to designate like parts throughout the same,

Figure 1 is a side elevation of several of the improved supports in use;

Fig. 2 is a plan view illustrating the manner of using the support;

Fig. 3 is a side elevation illustrating the support in use;

Fig. 4 is a perspective of one of the supports, and

Fig. 5 is a perspective of a shim embodied in the invention.

Fig. 6 is a detailed view illustrating a shim in place beneath the rail and overlapping the adjacent portions of the arms 9.

In the drawing, wherein for the purpose of illustration is shown a preferred embodiment of the invention, the numerals 5 designate a plurality of spaced parallel ties 50 set in the ground at uniformly spaced points to support a pair of rails 6. It is frequently desired to remove one and possibly two of the cross ties 5 for replacement and to support the rails during that period 55 I provide one or more temporary supports

8, each of which consists of similarly formed arms 9.

In carrying out the invention each of the arms 9 is formed from suitably stout metal having its outer portion hooked as indicated 60 at 10 for extending over a pair of temporary rails or supports 11.

As illustrated in Fig. 3, the temporary rails 11 are extended transversely of the cross ties and on opposite sides of the main 65 rails 6. The inner portions of the arms are extended angularly to provide rail supporting seats 14, the terminal portions of which are extended downwardly to provide ears 16. The ears 16 are apertured for the 70 reception of a fastening device 18 and when the fastening device is extended through the ears 16 and is fastened, the arms 9 are securely joined.

By making the improved temporary support in two pieces the same may be quickly applied without in any way disturbing the main rails 6. 75

In use when it is desired to employ the improved temporary support the arms 9 80 may be quickly positioned on opposite sides of the rail with the ears 16 beneath the base of the rail. The fastening device 18 may now be extended through the ears for securely and positively joining the arms. 85

If there is a space between the angularly directed portions 14 and the base of the rail a shim 20 may be inserted and Fig. 5 illustrates that the shim is provided with pairs of depending lugs 22 which are arranged on opposite sides of the angularly directed portions 14 and hold the shim in place.

Attention is especially directed to the fact that the shim plate 20 not only builds up 95 the seat for the rail but also provides an unbroken surface for the rail. This strengthens the connection between the angularly directed portions 14 and reduces the possibility of a break or rupture to a 100 minimum.

Having thus described the invention, what is claimed is:

1. A temporary support for rails comprising a pair of separately formed arms 105 having their outer portions provided with means for extending over relatively fixed supports, the inner portions of the arms being provided with angularly directed members for supporting the base of a rail and 110

the inner terminal portions of the arms being provided with apertured ears extended downwardly, and fastening devices extending through said ears for connecting said arms.

2. A temporary support for rails comprising a pair of separately formed arms having their outer portions provided with means for extending over and engaging 10 relatively fixed supports, the inner portions of the arms being provided with angularly directed members for supporting the base of a rail and the inner terminal portions of the arms being provided with apertured 15 ears extended downwardly, fastening devices extending through said ears for connecting said arms, and a shim mounted on the angularly directed inner portions of

said arms and overlapping the same to provide an unbroken surface for supporting 20 the rail.

3. A temporary support for rails comprising a pair of separately formed arms having their inner portions extended angularly to provide a seat, the inner terminal 25 portions of the arms being extended downwardly at right angles to said seat to form a pair of ears, fastening means joining said ears, and a shim mounted on the seat of said arms and adapted for supporting 30 a rail, said shim being provided with pairs of depending lugs arranged on opposite sides of said seat.

In testimony whereof I affix my signature.

JOHN LAVIGNA.
